UNITED STATES PATENT OFFICE

2,427,205

FOLDING PUSH CAR OR WHEELED CHAIR

Reginald Clarence Ford, Allesley, near Coventry,
EnglandApplication March 8, 1946, Serial No. 652,961
In Great Britain July 3, 1945

5. Claims. (Cl. 280—39)

1

This invention relates to certain improvements in pushcars or wheeled chairs of the kind described in the specification of my prior U. S. Patent No. 2,415,629, that is to say, of the kind comprising a collapsible structure adapted when extended to support a seat and back-rest, and resilient means hinged to said structure about a fore and aft axis and extending along each side thereof to carry a wheel at each end.

An object of the present invention is to provide improved means for locking the collapsible structure in its extended state.

Another object of the invention is to provide increased lateral support for the wheels in their position of use.

A further object of the invention is to provide improved means for locking the two parts of the folding handle in the extended state.

The locking means employed according to the present invention is arranged at each side of the collapsible structure and consists of a bar one end of which is pivoted about a horizontal transverse axis at or near the middle of the bottom horizontal member of said structure. The other end of this bar extends forward and carries one end of the foot rest.

The lower end of the front member at each side of the structure is extended so that when the structure is unfolded, the extension of said front member overlaps the bracket or hanger for the front wheel. In its operative position each locking bar occupies a forwardly and downwardly inclined position, its forward part overlapping the extension of the front member aforesaid thereby supporting the hanger at the outside. The bottom edge of said bar may be notched to engage pegs on the hinge plate and on said extension. The said front wheel hangers are supported laterally on the inside by the ends of the foot rest when the chair is extended.

Lateral support for the hangers of the rear wheels when in use is provided at the outside by extending the lower ends of the rear members of the collapsible structure, and at the inside by means of a transverse bar the end portions of which are secured to the said rear members and formed so that when the chair is in its extended state they overlap and support the said hangers on the inside.

In the accompanying drawings,

Figure 1 is a side view of the improved pushcar or wheeled chair.

Figure 2 is a rear view thereof.

Figure 3 is a side view of the pushcar partially folded.

2

Figure 4 is an underside view of Figure 1.

Figure 5 is an underside view of Figure 3.

Figures 6 and 7 are detail views on an enlarged scale of the means whereby the wheel mountings are hinged to the main frame.

Figures 8 and 9 are detail views on an enlarged scale of the means of lateral support provided for the front and rear wheels respectively.

Figure 10 is a detail view on a further enlarged scale of the means of locking the folded handle in the extended position.

Referring to Figures 1 and 2 it will be seen that the pushcar or wheeled chair comprises a pair of collapsible frames spaced apart in parallel planes 15 constituting a collapsible superstructure each frame being of parallelogrammic construction comprising upper and lower horizontal members *a*, *b* pivotally connected at their ends with front and rear members *c*, *d* respectively.

20 For this purpose the members *a* may be formed as arm rests and the members *b* may be united by integral stays in the form of a single pressing.

The back *e* of the chair is carried by the rear members *d* by means of a horizontal bar *e*¹ and 25 is pivoted at its lower end to the seat *f* which, in turn is pivoted to the front members *c*.

The improved locking means for locking the frames aforesaid in the extended position and hence the pushcar itself, comprises bars *g* freely 30 pivoted on the horizontal members *b* at one end and carrying at the other end the footrest or step board *h* in a pivoted manner. The bars or struts *g* are provided with one or more notches 35 which to lock the pushcar in the extended position are engaged with pins or studs *c*² fixed to extensions *c*¹ of the front members *c*.

The provision of one or more notches enables 40 the pushcar to be locked and used at different angles, i. e. a choice of angle of the chair back to the seat *f* is given.

Each pair of wheels is pivotally mounted about 45 a fore and aft axis, the wheels *l* of each pair being carried by brackets or hangers *m* from the ends of blade spring *n* extending in a fore and aft direction and having a hinged connection with the adjacent horizontal member *b* of the frame.

For this purpose, as shown in Figures 6 and 7, a member *o*, attached to the top of the blade spring *n* has journalled in it a pin *p* about which 50 is pivoted a hinge plate *q* attached to the frame *b* or integral therewith.

The manner of hinging is such that the wheels 55 can be folded underneath the chair.

As shown in Figure 8, lateral support is given to front wheel hangers from the inside by the

step board *h* and from the outside by means of the extensions *c*¹ of the front members *c*.

The rear members *d* may be formed in one piece to provide the lower horizontal member *d*¹ and formed to provide inside support for the rear wheel hangers in conjunction with outside support members *d*² attached to the members *d*, as shown in Figure 2 and in enlarged detail in Figure 9.

The folding handle has for its lower members the members *d* at the upper ends of which are pivoted the upper member *r* which carry the handlebar *s*. At or near the pivoted ends of the members *d* and *r* are attached horizontal bars *d*³ and *r*¹. The lower bar *d*³ has pivoted at the back and near each end catches *t*, *t*, which by engaging the back of the upper bar *r*¹ lock the handle in the extended position, see Figure 10.

To fold the handle the catches *t*, *t* are turned in a downward direction to the position *t*¹, *t*¹ whereupon the handle can be folded back about the two pivoted joints.

To continue folding the pushcar the step-board *h* is lifted to lift the locking bars *g* clear of the pins *c*², as shown in Figure 3, whence the chair can be collapsed in a forward direction. At the same time the extensions *c*¹ and rear lateral support means provided by the bar *d*¹ and members *d*² are raised clear of the wheel hangers. By turning the step-board about its pivotal connection with the ends of the bars *g* the wheels are freed of all lateral support and can be folded underneath the chair.

The wheels when folded may normally tend to slightly overlap but by pushing them apart against the action of the blade spring they may be caused to be locked in position by the tyres or rims making firm contact with one another due to the action of the blade springs, as shown in Figure 5.

I claim:

1. A folding pushcar having a collapsible superstructure and inwardly folding wheels mounted

on resilient means, said car incorporating struts adapted to secure the superstructure in its open position, and a footrest mounted on said struts and adapted to come between and secure the wheels in their open condition.

5 2. A folding pushcar having a collapsible superstructure and inwardly folding wheels mounted on blade springs, said car incorporating struts pivoted to a horizontal member of the superstructure and slotted to engage studs on a downward member, and a footrest mounted on said struts and adapted to come between and secure the wheels in their open condition.

10 3. A folding pushcar having a collapsible superstructure and inwardly folding wheels mounted on blade springs, said car incorporating struts pivoted to a horizontal member of the superstructure and slotted to engage studs on a downward member, a footrest mounted on said struts and adapted to come between and secure the wheels in their open condition, and an extension of a downward member of the superstructure adapted to laterally support the wheel carrying frame.

15 25 4. A folding pushcar as claimed in claim 2 wherein the inwardly folding wheels frictionally contact each other in the folded position by virtue of the supporting blade springs.

20 30 5. A folding pushcar as claimed in claim 2 having a folding handle which has pivotal catch members cooperating with horizontal bars for the purpose set forth.

REGINALD CLARENCE FORD.
